13 Claims. (Cl. 299—88)

1

The present invention relates to liquid spraying or atomizing devices, and particularly to a device of the described character which may be conveniently attached to the mouth opening of a container.

An object of the present invention is to provide a liquid spraying or atomizing device for attachment to the mouth opening of a container which includes a duct in part defining an intermediate chamber, preferably filled with an absorbent material, and manually actuatable means for placing the duct in communication with the associated container, and wherein the device is constructed and arranged so that a first actuation of the manually actuatable means, with the container in an inverted or overturned condition, causes filling of the intermediate chamber with liquid from the container, and a subsequent actuation of the manually actuatable means produces a stream of air effective to discharge the liquid from the intermediate chamber into the atmosphere in the form of an atomized spray and without regard to the position of the container during such subsequent actuation.

A further object is to provide a spraying or atomizing device having the foregoing characteristics and wherein leakage of liquid from the associated container is positively prevented until the manually actuatable means is actuated so that the container and atomizing device may be stored, for example, in luggage, in an inverted position without the risk of damaging surrounding articles of wearing apparel by reason of leakage from the container.

In accordance with the present invention, the above objects are achieved by providing a spraying or atomizing device which comprises a body member attachable in the manner of a cap or plug to a container and constituting a cylinder, a piston member sealingly slidable in this cylinder and subjected to the action of a spring, an axial duct rigid with the piston and slidable in a bore formed at the base of the plug, a part of said duct forming an intermediate chamber in which fluid from the container may be stored, said chamber being supplied from the container through a valve member which is normally sealed when said piston is subjected to the action of its spring in idle condition, and an air-vent or port providing communication from said duct to the space enclosed by said cylinder and piston. The axial duct is formed near its inner end with a lateral supply aperture in its wall which is normally sealed by the adjacent wall of the bore but is adapted to be put into communica-

tion with the interior of the container upon depression of the piston and the duct is sealed by a valve member which normally seals the inner end of said bore, said valve member being preferably in the form of a valve head provided with a seal ring and defined by the head of a screw-plug rotatable to adjust the effective passage area of said supply aperture. The above-mentioned air-port is preferably formed in the sidewall of the duct in a restricted portion thereof adjacent to its mouth opening.

The objects, features and advantages of the invention will become fully apparent from a study of the ensuing description relating to some exemplary embodiments of the invention given by way of example and not of limitation with reference to the accompanying drawings in which:

Fig. 1 is an axial sectional view of a first embodiment of the improved spraying device, part of the bottle to which it is attached being shown;

Fig. 2 is a fragmentary view of a modification of the embodiment of Fig. 1;

Fig. 3 is an axial sectional view of another embodiment of the device adapted for attachment to the bottom of a container, such as, for example, an oil or vinegar cruet;

Fig. 4 is a complete axial sectional view of another modification of the device as embodied for instance in a portable perfume atomizer; and

Fig. 5 is an axial sectional view of still another embodiment of the present invention.

As shown in Fig. 1, the improved spraying device may be provided in the general form of a cylindrical assembly adapted for attachment, in the manner of a plug or cap, to the mouth of a container such as a bottle or flask 1, for example by screwing an internally-threaded central base portion 3 of the assembly over the threaded neck 2 of the bottle with a seal ring 4 interposed between the neck 2 and the base portion 3. The end wall 5 of the base part 3 is formed with a boss 6 provided with an axial bore 7 fitted with a seal ring 8 and adapted to receive therein an axially slidible tube to be described later. Crimped in the bottom periphery of the base portion 3 there is a generally cylindric concentrical shell 9 which provides an external cylinder in which an actuating member or piston is slidable.

In the present instance this actuating piston is provided in the form of a press-formed cup-member 10 formed at its open base with spaced slots 11 having enlarged ends so as to define resilient teeth 12 between the adjacent slots. Over the vertical extent of these slots the outer sur-

face of the piston 10 is provided with an annular coating of a moulded plastic material 13 such as synthetic rubber or the like anchored in the slots and providing a suitable backing or contact surface against the inner surface of the cylindrical shell 9. The end wall of the piston is substantially flat and is subjected to the upwardly directed yieldable force exerted by a coil spring 14 which is seated against the bottom wall of the cylinder or shell 9. The end wall of the piston 10 is shown formed with an annular seating surface for a label or indicating element 15 and further with a central reentrant depression 16 which provides the discharge opening of the spray device. Secured in this discharge opening 16 is a duct 17 which is formed in its side wall near its outer or discharge end with a port 18 providing communication at all times between the inside of the duct 17 and the space or enclosure defined between the cylinder 9 and the piston 10. The duct 17, which is comparatively restricted in cross-section, is extended by a section 19 of substantially wider diameter slidably in the previously-mentioned bore 7 in the base or plug portion 3 of the assembly. The lower end of the duct section 19 is internally threaded and receives a screw 20 which thus seals the duct. The screw 20 is formed with a head 21 fitted with a seal ring 22 and provides a valve head normally sealing the bore 7, being seated against the lower surface of the end wall 5 of the base or plug portion 3 under the action of the spring 14 which acts upwardly against the top of the piston. The larger-diameter section 19 of the duct defines an intermediate chamber and is formed with a supply aperture 23 in its side wall near its lower end; the aperture 23 being normally sealed by the seal ring 8 of the bore 7 when the piston 10 is in its uppermost, idle, position with the valve head 21 in sealing engagement with the wall 5, and the useful area of the aperture 23 may be adjusted by screwing the screw-plug 20 more or less deeply into the duct 19. The wider section 19 of the duct which forms an internal storage or intermediate chamber is preferably filled with a body of absorbent material 24 such as cotton-wool, a wick, or the like.

The device operates as follows:

With the container 1 full of liquid and so long as the piston 10 is not actuated or manually depressed into the cylinder 9, the valve-head 21 is applied against its seat and the container is and remains perfectly sealed. When it is desired to spray liquid, the flask is grasped in one hand, with two fingers resting on the top of the piston 10 to either side of the discharge outlet 16. The flask is then turned upside, while pressing down on the piston to cause the latter to telescope into the cylinder or shell 9. This causes the air contained in the cylinder-and-piston enclosures to escape through the port 18 and duct 17 out through the outlet 16. At the same time the valve 21 is unseated and the aperture 23 clears the inner or entrance end of the bore, providing a communication from the interior of the container to the duct 19. Liquid flows through the aperture and wets the absorbent filling 24 in the duct 19. When the piston is released, the valve head 21 returns to its seated position and the aperture 23 is again closed by the seal ring 8, but this time the wick or filling 24 is impregnated with liquid. As the piston rises again in response to the force exerted by the spring 14 air again enters the enclosure between the piston 10 and the cylindrical shell 9. With the bot-

tle now held in any desired position, if the piston is once more depressed, the air is compressed by the downward or telescoping motion of the piston 10 and escapes through the small diameter port 18, inducing within the duct 17-19 a suction which draws out and discharges in an atomized spray part of the liquid impregnating the wick or absorbent filling 24. If the second actuation of the piston is effected with the bottle upside down, the wick again becomes impregnated and the spraying operation can be continued as long as there is any liquid remaining in the bottle. However, if the bottle is in its normal upright position when the piston 10 is depressed for the second time, liquid from the container cannot re-enter the duct to again wet the wick and only the amount of liquid that impregnated the wick can be sprayed before the container is again inverted to replenish the supply of liquid in the wick or filling 24.

It will thus be seen that the large-diameter section 19 of the duct acts as an intermediate or storage chamber which may be supplied with liquid to be sprayed by depressing the piston while holding the bottle upside down, but which even then remains practically isolated from the container throughout the greater part of the piston's travel. With a proper relative dimensioning between the size of the intermediate chamber 19 and that of the cylinder 9, a metering device may be obtained, the supply of liquid in the intermediate chamber becoming exhausted at the end of any predetermined number of actuations of the piston. It should be noted that the rate of intake of air is always sufficient to enable normal and free outflow of the liquid from the container into and through the duct 17-19 when the valve head 21 is unseated and the aperture 23 is opened. On the other hand, the suction induced in the duct by the escape of air from the cylinder through the port 18 is not applied within the container by reason of the filling 24 within the chamber or duct portion 19, but only within the comparatively restricted capacity of the duct 17 itself in which its action is accordingly extremely efficient. This ensures that the spraying operation is very satisfactory.

Moreover, and this is an essential advantage of the invention, the container is hermetically sealed automatically and in a perfectly positive and safe manner when not in use, without requiring any additional manipulation to achieve this purpose as do conventional sprayers. Thus, in the form of embodiment described above, this sealing function is performed by the valve head 21 which, upon release of the piston 10, is immediately applied against its seating by the piston spring 14.

In the above-described embodiment of the invention, discharge in the form of spray of the liquid impregnating the absorbent filling 24 in the intermediate chamber 19 was accomplished, as stated, by the suction induced adjacent to the outlet of the duct by the expulsion of air. It is also within the scope of the invention to produce the spraying discharge by a stream of air delivered into the base of the duct. Such an arrangement is shown in Fig. 2, wherein the parts corresponding to those of Fig. 1 are identified by the same reference numerals with the letter "a" appended thereto. As shown, the duct part 19a is formed with an air-port 25 at a point thereof somewhat above the part of the duct inserted into the bore 7a; however, the upper port 18 may still be retained herein to serve as an auxiliary

with its diameter being substantially restricted relatively to that of the main port 25. The supply aperture, which in Fig. 2 has been shown, merely by way of example, in the form of a duct 26 formed through the screw 20a and which may have the area of its inlet adjusted by rotation of the screw, must in this case be provided with a check-valve shown simply as a ball 27 seated in a recess 28 surrounding the outlet of said duct 26. The check-valve is necessary in the arrangement of Fig. 2 because of the necessity to prevent passage of air from the lower aperture 25 through the lower rather than the upper end of the duct.

As in the first embodiment, the duct 19a is supplied with liquid when the flask is overturned and the piston 10a is depressed, the ball 27 then being unseated by gravity. After the wick 24a has become saturated with liquid, this liquid can then be sprayed by a few rapid strokes of pressure imparted to the piston 10a. Each time the piston goes down, compressed air from the enclosure defined by the piston 10a and the cylinder 9a enters the duct 19a through the aperture 25 and liquid is discharged both by the pressure of this air and by the suction created towards the outlet of the duct by the air passing through the auxiliary port 18a. The latter port may in some cases be omitted.

As shown in Fig. 3, a similar device may be applied to the bottom rather than to the top of a container, such as, for example, a vinegar or an oil cruet. In this embodiment, a part 29, made of a moulded plastic for example and comprising both the body of the plug for attachment to the container and the cylinder, is screwed to the bottom outlet of a container 30 with a seal 31 interposed between the container outlet and the part 29. The piston herein is provided by a leather cup member 32 secured to the top of a part 33 forming a stand or base, the member 32 being clamped against the part 33 by the flange 34 of a tube 35 which provides the axial duct and is secured to the base 33 by a threaded connection 36. The flange 34 is formed with holes 37 and the base 33 is formed with ducts 38 extending angularly from the holes 37 and opening into the end of an axial duct 39 of restricted diameter which connects the duct 35 with a discharge outlet 40 for the sprayed liquid. It will be seen that the ducts 39 and 35 are functionally equivalent to the ducts 17 and 19, respectively, of Fig. 1. The duct 35 which is rigid with the stand-and-piston assembly 33—32 defines an intermediate or storage chamber and contains absorbent filling 41. The duct 35 is axially slidable in a bore 42 in the bottom of the plug 29, and is sealed at its end remote from the base 39 by a screw 43 provided with a conical head which forms the valve member for sealing the bore 42. A port 44 is provided in the wall of the duct 35 adjacent the screw 43 and is normally sealed but provides communication between the container and the interior of duct 35 when the piston 32 is moved into the cylindrical body 29. A spring 45 normally maintains the container in raised condition relatively to the base and accordingly retains the valve 43 in its seated condition.

When the stand is raised relatively to the container 30, the piston 32 is forced into the cylinder 29 and the hole 44 is uncovered within the container, thus enabling liquid to enter and impregnate the wick 41. A subsequent movement of the piston 32 into the cylinder 29 expels air from the cylinder through the ducts 38 and

causes liquid to be sprayed downwardly from the outlet 40 at the center of the stand, the liquid impregnating the wick 41 being drawn through the duct 39 by suction induced by the air flowing through the ducts 38.

Fig. 4 illustrates a form of the invention as embodied in a travelling atomizer or perfume sprayer or the like. The body of the atomizer or container is adapted to receive at its top a sprayer plug 47 which according to the invention has a cylindrical outer wall forming an extension of the side walls of the cylindrical container. In the construction shown, the container body is in two parts, the plug 47 being retained in position by a flange extending radially from the top of a central part 48 which is screwed into a boss 46a formed centrally on the top wall of a cylindrical outer container part 46. The central part 48 has a long tube 49 reaching down to a level near the bottom of the container. A hollow piston member 50 is slidable in the plug 47 and urged upwards by a spring 51 and terminates in an enlarged top or head 52 which may be provided with any desired ornamental pattern and is formed with a laterally-projecting outlet 53 instead of the axial outlet of the previously-described embodiments. A duct 54 formed in the body of the piston head 52 provides for the flow of air between the space defined by the plug 47 and piston 50 and the outlet 53. A radially extending spray tube 55 extends into the outlet 53 and branches-off from a central tube 56 which is slidable in the tube 49 and is provided at its bottom end with a valve 57 normally sealing the end of the tube 49. Extending through the piston head 52 at the side of the latter diametrically opposed to the outlet tube 55 there is a hole 58 provided with a screw plug 59 removal of which allows insertion of a pricker probe into said outlet tube in the event the latter should become clogged. The duct 56 which provides the intermediate or supply chamber for the spraying liquid contains a wick or absorbent filling 60 and is provided near its bottom end with a supply aperture 61 normally covered up by the tube 49.

In each of the above described embodiments, the spraying outlet or orifice is formed in the movable part of the air pumping or compressing assembly. However, if desired, the spraying outlet may be provided in the relatively stationary part of the air pumping assembly, as shown in Fig. 5. In the embodiment of Fig. 5, a plug or body 62 is formed with a threaded cylindrical recess for receiving the threaded neck of a container 63. The body 62 is formed with a central bore 64 extending axially therethrough and slidably receiving a stem 65 which has a valve head 66 on its lower end for seating against the bottom of the body 62 within the cylindrical recess of the latter. The body 62 has a bellows 67 extending thereabove, and a cylinder 68 is slidable on the bellows 67 and has the stem 65 secured thereto so that, as the cylinder 68 is worked up and down on the bellows, the stem 65 and valve head 66 are displaced relative to the plug or body 62. The bellows 67 is dimensioned so that it resiliently urges the cylinder 68 upwardly to a position in which the valve head 66 is seated against the body 62. When the cylinder 68 is depressed, against the force exerted by the bellows 67, the air inside the bellows is compressed and the valve head 66 is moved away from its seated position.

The body 62 is formed with a discharge passage or duct 69 opening radially outward and com-

municating with an intermediate supply chamber 70 which opens into the bore 64 and is filled with a wick or absorbent filling 71. A recess or cavity 72 is formed in the surface of the stem 65 in registry with the intermediate supply chamber 70 and is dimensioned to selectively place the latter in communication with either the interior of the bellows 67 or the interior of the container 63, as the stem 65 is displaced by depression of the cylinder 68. That is, when the cylinder 68 is in its raised (illustrated) position, the cavity 72 places the chamber 70 in communication with the interior of the bellows 67 so that initial depression of the cylinder 68, compressing the air in the bellows, causes the compressed air to flow through the chamber 70 for discharging the liquid stored in the absorbent filling 71 through the duct 69 in the form of an atomized spray. When the cylinder 68 is fully depressed, the cavity 72 ceases to be in communication with the interior of the bellows 67 and opens into the interior of the container and the chamber 70 so that the contents of the container 63 can then flow into the intermediate supply chamber 70 when the container is inverted or overturned.

Finally, the bellows 67 is formed with an in-turned flange or lip 73 along its upper edge, and the top wall of the cylinder 68 has openings 74 therein in positions normally covered by the flange 73. When the cylinder is depressed to an extent interrupting the communication between the interior of the bellows 67 and the cavity 72, the distortion of the bellows turns the flange 73 away from the top wall of the cylinder 68 to open the openings 74 for communicating the interior of the bellows with the atmosphere so that the cylinder 68 may be further depressed.

While illustrative embodiments of the invention have been described in detail and shown in the accompanying drawings, it is to be understood that the present invention is not limited to these precise embodiments and that various changes and modifications may be made therein without departing from the scope or spirit of the invention as defined in the appended claims.

What is claimed is:

1. Spraying attachment of the type described adaptable to a container opening, said attachment comprising a deformable enclosure including a fixed and a compressible part spring-urged to expanded condition, a duct rigid with said compressible part and extending at one end toward said container, means defining a valve seat on said fixed part of the enclosure, valve means carried by said duct for engaging said valve seat and sealing said duct from communication with the interior of said container in the expanded condition of the enclosure, and being removed from said seat to provide communication from the container to said one end of the duct in the contracted condition of the enclosure, absorbent means in said duct to receive an amount of the container's contents introduced into the duct by a first contraction of the enclosure when the spraying attachment is disposed with said one end of the duct uppermost so that said duct provides an intermediate capacity for the storage of the thereby received amount of the container's contents, and air-passage means between the enclosure and the duct whereby a renewed contraction of the enclosure causes a discharge of air from the enclosure through the duct effective to discharge in the form of spray said amount stored in the intermediate capacity.

2. Spray device as in claim 1 including a part

for plugging the container opening and having a bore formed therethrough in which said duct is slidably, a supply aperture in the side of the duct adjacent said one end thereof, said aperture being normally sealed by said plugging part but communicating with the interior of the container on depression of said compressible part, and wherein said valve seat means is formed by the face of said plugging part directed toward the interior of the container, and said valve means includes a head at said one end of the duct normally sealingly applied against said face of the plugging part.

3. Spray device as in claim 2 wherein said valve head is the head of a screw having its stem screwed into said one end of the duct and adjustable axially in the latter to close said side aperture by a selected amount and thereby alter the useful area of said side-aperture.

4. Spray device as in claim 1 wherein said fixed part of the deformable enclosure consists of a cylinder member rigid with a part for plugging the container opening and having a bore therethrough in which said duct is slidably, and said compressible part includes a piston member slidably in the top of the cylinder and spring-urged to its expanded position.

5. Spray device as in claim 4 wherein said piston member is in the form of an inverted cup member formed with resiliency-increasing slots extending from the free end of the cup over a predetermined vertical extent, and a resilient annular coating surrounding the piston over said extent, said coating being a moulded plastic anchored in said slots, providing a sliding seal surface engaging the inner wall of the cylinder member.

6. Spray device as in claim 1 wherein said duct includes a restricted portion at the opposite end thereof terminating in a discharge orifice and said air-passage means comprise a port in the side wall of the duct in said restricted portion of the duct downstream of said absorbent means, whereby the discharge of air through said port when the enclosure is contracted acts by suction to draw out the amount of substance stored in the capacity.

7. Spray device as in claim 1 wherein said air-passage means comprise a port in the side wall of the duct adjacent to said one end of the duct, whereby the discharge of air through said port acts by pressure to force out the amount of substance stored in the absorbent means, and ball check-valve means sealing said aperture against the entry of such air in the direction from said duct.

8. Spray device as in claim 1 wherein the attachment is adapted to be attached to the bottom outlet of a container, said compressible part being rigid with the top of a stand for the assembly, so that said enclosure is contracted when the stand is raised relatively to the container.

9. Spray device as in claim 1 wherein the attachment is applied to a portable scent-spray, said duct terminating in a lateral nozzle above said compressible part and forming a spray discharge outlet.

10. Spray device as in claim 9 wherein said fixed part includes a plug for closing the container opening and having an extension in the form of a tube reaching down to a level near the bottom of the container, and the duct rigid with said compressible part is a tube slidably in said tubular extension and provided with a valve head at its bottom engageable with the lower end of

said tubular extension to selectively open and close communication therethrough.

11. Spray device as in claim 1 wherein said depressible part includes movable cylinder member having said discharge duct rigid with it and extending axially thereof, and said intermediate capacity is in the form of a flat cylindrical chamber at the top of said duct, with a discharge outlet from said chamber.

12. Spray device as in claim 1 wherein said fixed part includes a piston member for plugging the container opening and said depressible part includes a movable cylinder slideable over said fixed piston member, and wherein the intermediate capacity is in the form of a horizontal chamber in the top face of said fixed piston plugging member and the spray outlet is in the form of a duct in said plugging member leading from said chamber to a point below said cylinder member.

13. Spray device as in claim 1, wherein said fixed part includes a piston member which has

an upwardly extended elastically deformable bellow seated against the top of the manually depressible cylinder member, and adapted to cover and uncover air-ports formed in said depressible part responsive to the alternately-exerted pressure and suction effects generated in the enclosure.
